UNITED STATES PATENT OFFICE.

WILLIAM R. M. TENNEY, OF BOSTON, MASSACHUSETTS.

TOY GUN.

SPECIFICATION forming part of Letters Patent No. 542,212, dated July 2, 1895.

Application filed April 29, 1895. Serial No. 547,475. (No model.)

To all whom it may concern:

Be it known that I, WILLIAM R. M. TENNEY, of Boston, in the county of Suffolk and State of Massachusetts, have invented certain new and useful Improvements in Toy Guns, of which the following is a specification.

This invention relates to that class of toy guns which are used for exploding paper caps; and it has for its object to provide a toy gun adapted not only to explode a cap, but also at the same time to expel a projectile from the barrel of the gun.

The invention also has for its object to provide a toy of this class with certain adjuncts—such as a whistle and a bird-call—whereby its capabilities may be increased. The invention consists in the improvements which I will now proceed to describe and claim.

Of the accompanying drawings, forming a part of this specification, Figure 1 represents a top view of my improved toy. Fig. 2 represents a side view of the same.

In the drawings, *a* represents a barrel having a longitudinal bore, and *b* represents a plunger which is fitted to reciprocate in said bore and is provided with a head or handle *b'* at its rear end, the latter being connected by a spring *c* with a suitable part of the barrel, the arrangement being such that when the plunger is retracted the spring is distended, and when the plunger is released the spring acts to forcibly project the plunger. The spring, as here shown, is a piece of elastic material passing through an orifice *b*³ in the head *b'* and suitably engaged with the forward portion of the barrel.

On the plunger *b*, I mount a cap-exploding hammer *d*, which forms one side of a cap-receiving recess *d'* and is arranged so that when the plunger is projected the hammer will strike the rear end of the barrel *a* and will thus be caused to explode a cap contained in said recess. I have here shown the hammer *d* as a ring or washer, which is preferably of metal, placed loosely upon the plunger *b* and in such proximity to the inner end of the head *b'* that the recess *d'* is formed by the adjacent surfaces of the hammer *d* and of the head.

e represents a trigger, which is pivoted at *e'* to the end of barrel and is arranged to en-

gage the barrel and hold the plunger in a retracted position, as shown in Fig. 2. The plunger being in this position and a cap inserted between the hammer and the head *b'*, a movement of the trigger, which releases the plunger, will permit the spring to forcibly project the plunger and thus cause the explosion of the cap when the hammer reaches the rear end of the barrel. At the same time the plunger projects from the barrel any projectile which may have been placed therein in advance of the plunger.

f f represent wire arms attached to the outer end of the barrel, said arms being formed and arranged to loosely hold a rubber ball or other projectile of larger diameter than the barrel. The plunger when projected enters the space between the arms, and therefore is adapted to eject from the arms any projectile that may be placed therein.

I do not limit myself to the arms *f* as the holder for the projectile, and may employ a holder of any desired construction adapted to hold an enlarged projectile outside of the barrel. It is obvious, however, that when a projectile of sufficient size to enter the barrel is employed the said holder will not be required. The sleeve *f'*, to which the arms *f* are affixed, may be removable from the barrel, and a tube may be substituted therefor adapted to contain smaller projectiles—such as beans.

g g' represent arms formed upon the barrel *c* and projecting laterally therefrom in opposite directions. Said arms constitute convenient means for holding the barrel, serving as handles therefor. One of the arms, as here shown, is constructed as a whistle having a mouth-piece *g*². The other arm may be utilized as a part of an acoustic toy known as a "bird-call," its outer end being here shown as provided with a cylindrical seat *g*³, upon which is placed a rotary cap *g*⁴. When the seat *g*³ is coated with resin and the cap *g*⁴ rotated thereon, a particularly disagreeable penetrating sound is emitted, which adds to the effectiveness of the aggregation.

The arm *g'* may have a chamber *g*⁵ to contain a series of the paper caps, the cap *g*⁴ serving as a cover for said chamber.

The head *b'* may have a slot *b*³ open at its rear end to receive and prevent the removal

of the spring, so that the spring may be disengaged from the plunger and caused to impel an arrow, the plunger being removed and the arrow placed in the barrel in place of the 5 plunger.

Fire-crackers may be expelled from the barrel by the plunger, the crackers being ignited before being expelled.

I claim—

- 10 1. A toy gun comprising a barrel, a spring-actuated plunger movable in said barrel, and a hammer which is movable upon the plunger and forms one side of a cap-holding recess, said hammer being arranged to abut 15 against a part of the barrel when the plunger is projected and thereby explode a cap inserted in said recess.

2. A toy gun comprising a barrel having a

lateral arm provided with a whistle, a spring-actuated plunger movable in said barrel, and 20 a cap-exploding hammer on said plunger.

3. A toy gun comprising a barrel having two lateral arms, one provided with a whistle and the other with a seat and a cap rotatable thereon, a spring-impelled plunger movable 25 in said barrel, and a cap-exploding hammer on said plunger.

In testimony whereof I have signed my name to this specification, in the presence of two subscribing witnesses, this 22d day of 30 April, A. D. 1895.

WILLIAM R. M. TENNEY.
